C. E. PEARCE

STOP MOTION FOR SPINNING FRAMES

Filed Feb. 9, 1922

UNITED STATES PATENT OFFICE.

CHARLES E. PEARCE, OF COOLEEMEE, NORTH CAROLINA, ASSIGNEE OF ONE-EIGHTH
TO JOHN S. STROWD, ONE-FOURTH TO CHARLES W. ALEXANDER, AND ONE-FOURTH
TO JAMES W. ZACHARY, OF COOLEEMEE, NORTH CAROLINA.

STOP MOTION FOR SPINNING FRAMES.

Application filed February 9, 1922. Serial No. 535,235.

To all whom it may concern:

Be it known that I, CHARLES E. PEARCE, a citizen of the United States of America, and a resident of Cooleemee, county of Davie, and State of North Carolina, have invented certain new and useful Improvements in Stop Motions for Spinning Frames, of which the following is a full and clear specification.

10 The object of this invention is to provide a simple mechanism which will not only stop the operation of the machine, but will also lower the ring-rail automatically, upon the completion of the windings of the bobbins, as more fully hereinafter set forth.

In the drawing annexed—

Fig. 1 is a plan view of a part of a spinning frame, enough of the spinning-frame being shown to illustrate the manner in which my invention is applied thereto;

Fig. 2 is a view partly in side elevation and partly in section of the mechanism shown in Fig. 1;

Fig. 3 is a detail view of a part of the tripping mechanism.

In the drawing annexed, 5 designates the usual traverse screw, on which runs the usual traverse-nut 6, which nut is connected by chain 7 and other mechanism, not shown, with the ring-rail. This traverse-screw is, as usual, carried by an oscillating bar 8 which is moved intermittently up and down by the usual mechanism, not shown, the screw 5 being stepped around with each reciprocation of the bar 8 by means of the usual ratchet mechanism 9.

Attached to the usual nut 6 is an upstanding arm 10, to the upper end of which is pivotally connected a trip-rod 11, the free end of this rod 11 being slotted at 12 for pivotal and slidable connection with the upper end of the crank-arm 13 carried by a rock-shaft 14, said trip-rod 11 being provided with adjustable stops 15—15' at either side of the connection with the crank-arm 13, to thereby give the rod 11 a limited sliding action with reference to the crank-arm 13. The rock-shaft 14 is provided with a

depending crank-arm 16 which at its lower end has a pivot-and-slot connection with a trip-pin 17 slidably mounted in the frame. When this trip-bolt 17 is projected in the position shown in Fig. 3, its end is in position to support a weight 18, which when released puts the stopping mechanism into operation, as hereinafter set forth. In starting, the nut 6 is, as usual, at the inner end of the traverse-screw and the stop 15 is against or close to the upper end of the crank-arm 13. As the bobbins are wound in the usual manner and the nut 6 travels toward the outer end of the screw, the trip-rod 11 will be carried along with it until the stop 15 engages the upper end of the crank 13 and thus rocks shaft 14, carrying trip-pin 17 from under the weight and thus allowing the same to drop, thereby putting the stop mechanism hereinafter described into operation. To restore the parts of this tripping mechanism to operative position, the traverse-screw is reversed by means of a hand-crank or otherwise, in the usual manner, to run back the nut 6, whereupon the stop 15' will engage the upper end of crank-arm 13 and thus return the trip-pin 17 to operative position. The oscillation of the traverse bar 8 on its pivot 11' will, of course, impart oscillation to the parts 10 and 11, but this will be an idle movement of these parts 10 and 11, since these parts do not function until either one or the other of the stops 15—15' makes contact with the crank-arm 13.

The weight 18 is slidably attached to a substantially radial arm 19 affixed to one face of a mutilated bevel-gear 20. Meshing with this gear 20 is a pinion 21 which is continuously rotated during the operation of the spinning-frame from the same source of power that operates the spinning-frame. For operating this bevel-pinion 21, I have shown a train of gearing 22 to connect up its shaft to the traverse gear on the spinning-frame or any other shaft that is continuously rotated during the running of the machine. While the machine is in opera-

tion and weight 18 is resting upon the trip-pin 17, the bevel-pinion 21 will be opposite the mutilated part of the gear 20 and will, therefore, have no rotative effect upon the 5 same. When, however, the trip-pin is withdrawn by the mechanism above described, the weight will drop and will rotate gear 20 far enough to bring its teeth into mesh with the bevel pinion 21. From that point, the 10 power for operating the stopping mechanism will be derived from said gear 21.

The shaft on which gear 20 is affixed is provided with a segment 23 which, when the gear is rotated counter-clockwise, will engage 15 the teeth of the sliding rack 24 and, through the medium thereof, stop the machine. As one means for stopping the machine, I have shown a pivoted lever 25 connected at one end to the rack-bar and at its 20 other end with rod 26, which is connected to the stopping-and-starting lever 27. In this instance, the hand-lever 27 is part of the mechanism for shifting the belt from the tight to the loose pulley, but it will be understood 25 that this lever may be a switch-lever, if the machine be driven electrically. The rod 26 has a slidable connection with the lever 25, and the inner end of the rod 26 is provided with a nut-stop 28. In Fig. 2, 30 the parts 27 and 26 are shown in full lines in stopping position and in dotted lines in running position.

When the weight falls and the segment is brought into mesh with the rack 24, the 35 power derived through the bevel-pinion 21 will rotate the segment to the left far enough to stop the machine, at which point the segment will leave the rack and will lie at the side opposite from that where it normally 40 lies. The weight will also have made about half a turn. When the parts stop in this position, the bevel-pinion will still be in mesh with the teeth on the gear 20 and it is obvious that the friction of the parts will prevent 45 the weight 18 from reversing the rotation of the parts. The parts will remain in this position until the machine is again started by throwing over the hand-lever 27, whereupon the bevel-gear 21 will again begin 50 to rotate and thus rotate gear 20 counter-clockwise. The rotation of gear 20 will continue until the pinion 21 again reaches the blank space in the gear, whereupon the gear 20 will be released from the pinion 21. By 55 the time this gear 20 is released from the pinion 21, the weight 18 will have been carried over far enough to rest upon the previously-restored trip-pin 17, and the parts will be again in position to repeat the operation 60 when the traverse mechanism again trips pin 17. It will thus be noted that the same source of power that drives the spinning machine operates the stopping mechanism and, further, that the same source of

power restores the stopping mechanism to 65 operative position when the spinning-frame is first started up again.

In the usual spinning-frame, a hand-lever 29 is provided for lowering the ring-rail, the mechanism operated by the shaft 30 of this 70 lever being not shown and the ring-rail also being omitted from my drawing. In the usual machine, the lever 29 is swung downwardly to lower the ring-rail, and a latch is usually employed to lock the ring-rail down. 75

To perform this operation automatically, when the machine is stopped by my mechanism, I provide the following simple mechanism: I attach to the shaft of the gear 20 an upstanding arm 31 and connect this arm by means of a chain 32 with an upstanding arm 33 affixed to the shaft 30. When the stopping mechanism operates, the first action of this mechanism will be to pull the lever 33 downwardly toward the left far enough to lower the ring-rail and permit it to be latched down by the usual latching mechanism. The latching occurs just as the arm 31 passes over center (i. e., a line drawn from the axis of the shaft carrying said arm 31 and the connection between the chain and the arm 33). After arm 31 thus passes over center, the chain 32 is slackened. Then, after the bobbins have been changed and the ring-rail latch released, the parts 31, 32 and 33 will be restored to operative position when the machine is again started up through the medium of the control lever 27.

I do not desire to be understood as limiting myself to the precise details of construction and arrangement shown, as variations and modifications therefrom may be made without departing from the spirit and scope of my invention and improvements. I therefore reserve the right to all such variations and modifications as properly fall within the scope of my invention and improvements and the terms of the following claims.

What I claim is:

1. In combination with a spinning-frame, a stopping mechanism, and a tripping means for said stopping mechanism operated from the usual nut of the swinging traverse-screw of the builder mechanism.
2. In combination with a spinning-frame, a stopping mechanism, and a tripping means for said stopping mechanism operated from the usual traverse-screw of the builder mechanism, said means being pivotally connected to the usual traverse-nut on the swinging traverse-screw.
3. In combination with a spinning-frame, a stopping mechanism, and a tripping means for said stopping mechanism operated from the usual traverse-screw of the builder mechanism, said means being connected to the usual traverse-nut on the traverse-screw, devices being provided whereby the running

back of the traverse-nut will restore the tripping means to normal.

4. In combination with a spinning-frame, a tripping means operated by the builder mechanism, and a stopping mechanism put into action by said tripping means, said stopping means embodying devices which complete the stopping operation and simultaneously lower the ring-rail through the same source of power which operates the spinning-frame.

5. In combination with a spinning-frame, a tripping means operated by the builder mechanism, a stopping mechanism put into action by said tripping means, said stopping means embodying devices which complete the stopping operation through the same source of power which operates the spinning-frame, said stopping devices embodying a driving pinion and a mutilated gear, and means for bringing them into mesh when the tripping means is operated.

6. In combination with a spinning-frame, a tripping means operated by the builder mechanism, and a stopping mechanism put into action by said tripping means, said stopping means embodying devices which complete the stopping operation through the same source of power which operates the spinning-frame, said stopping mechanism embodying a gravitating weight adapted to be released by the tripping means to put the power means into action.

7. In combination with a spinning-frame, a tripping means operated by the builder mechanism, and a stopping mechanism put into action by said tripping means, said stopping means embodying devices which complete the stopping operation through the same source of power which operates the spinning-frame, said stopping mechanism embodying a continuously-running driving pinion, a mutilated driven gear, and a weight attached to said gear and normally supported by a part of the tripping means and adapted when released by the tripping means to actuate the mutilated gear into mesh with said pinion, for the purpose set forth.

8. In combination with a spinning-frame, a tripping means operated by the builder mechanism, and a stopping mechanism put into action by said tripping means, said stopping means embodying devices which complete the stopping operation through the same source of power which operates the spinning-frame, said stopping mechanism embodying a slideable rack, a segment engaging said rack, and means actuated by the rack for stopping the mechanism.

9. In combination with a spinning-frame, a tripping means operated by the builder mechanism, and a stopping mechanism put into action by said tripping means, said

stopping means embodying devices which complete the stopping operation through the same source of power which operates the spinning-frame, means being also provided for automatically lowering the ring-rail when the stopping mechanism is operated.

10. In combination with a spinning-frame, a stopping mechanism operated by the same power that operates the spinning-frame, and an automatic tripping mechanism, said stopping mechanism embodying a rotary shaft, a ring-rail-lowering mechanism embodying a rock-shaft adapted when rocked to lower the ring-rail, and flexible means connecting these two shafts, for the purpose set forth.

11. In combination with a spinning-frame, a stopping mechanism and an automatic tripping mechanism therefor, said stopping mechanism embodying a gear continuously driven from the spinning-frame mechanism, a mutilated gear having its mutilated part normally opposite the aforesaid gear, means whereby when the tripping mechanism operates the mutilated gear will be put into mesh with said continuously-running gear, and means whereby a partial rotation of the mutilated gear will stop the spinning-frame and upon completion of the rotation thereof will start it again.

12. In combination with a spinning-frame, a stopping mechanism and a tripping mechanism therefor embodying a slideable tripping pin and means operated from the traverse-screw of the builder mechanism for moving said pin alternately in opposite directions.

13. In combination with a spinning frame, an automatic stopping mechanism operated from the same source of power that operates the spinning-frame, and an automatic tripping mechanism for said stopping mechanism, said stopping mechanism embodying devices whereby during its operation the spinning-frame will be stopped and also the stopping mechanism will be automatically restored to normal operative position.

14. In a spinning-frame, a rock-shaft associated with the usual ring-rail lowering mechanism and provided with an arm, a rotary shaft provided with an arm connected to the aforesaid arm by a flexible connection, as a chain, means operated from said rotary shaft for stopping the operation of the spinning-frame, means for driving said rotary shaft from the same source of power that drives the spinning machine, and automatic tripping means for putting said last-named means into operation when the bobbin-winding is completed, whereby when the spinning-frame is stopped the aforesaid arms and flexible connection will operate the ring-rail lowering means.

15. In a spinning machine, a builder mechanism embodying a traverse-screw

mounted on a swinging frame and having a traverse-nut, a tripping means operated from this nut and embodying a rod pivotally connected to the nut, a rocking member actuated alternately in opposite directions from said rod, a tripping-pin actuated by said rocking member, and an automatic stopping

mechanism adapted to be released when said pin is actuated in one direction and to be held out of action when it is actuated in the opposite direction. 10

In testimony whereof I hereunto affix my signature.

CHARLES E. PEARCE.
